UNITED STATES PATENT OFFICE

112,189

DESIGN FOR A LAMP SHADE

William H. Biever, Philadelphia, Pa.

Application July 8, 1938, Serial No. 78,344

Term of patent 7 years

To all whom it may concern:

Be it known that I, William H. Biever, a citizen of the United States, residing at Philadelphia, in the county of Philadelphia and State of Pennsylvania, have invented a new, original, and ornamental Design for a Lamp Shade, of which the following is a specification, reference being had to the accompanying drawing, forming part thereof in which,

Fig. 1 is a view in side elevation of a lamp shade embodying my new design, and

Fig. 2 is a top plan view thereof.

The figures of the drawing show a partial illustration of the corrugations and dots, it being understood that a complete illustration thereof would involve a mere repetition of that shown between the broken lines.

The design is characterized by ruchings of substantial width at the top and bottom of the shade which is of materially greater diameter at the bottom than at the top and is distinctly flared outwardly toward the bottom between said ruchings, the flared material comprising uniformly pleated dotted fabric whereby the dots form a pattern comprising spaced groups in spiral rows, those adjacent the crests of the pleats being more prominent than those remote therefrom.

I claim:

The ornamental design for a lamp shade, as shown and described.

WILLIAM H. BIEVER.
